Primary Examiner — Martie K Holtje(74) *Attorney, Agent, or Firm* — Eckert Seamans Cherin & Mellott, LLC; John P. Powers(57) **CLAIM**

The ornamental design for an amusement toy, as shown and described.

DESCRIPTION

FIG. 1 is a top perspective view of an amusement toy showing our new design;

FIG. 2 is a bottom perspective view thereof;

FIG. 3 is a top plan view thereof;

FIG. 4 is a bottom plan view thereof; and,

FIG. 5 is a front elevational view thereof, it being noted that the left, right, and rear elevational views are identical thereto. The structural features depicted by broken lines have been shown for the purpose of illustrating portions of the amusement toy that form no part of the claimed design.
